Des. 238,308
Patented Dec. 30, 1975

238,308

SPECIMEN COLLECTOR OR SIMILAR ARTICLE

Michael H. Sherin, P.O. Box 124, Fontana, Wis. 53125

Filed Apr. 12, 1974, Ser. No. 460,589

Term of patent 14 years

Int. Cl. D24—04

U.S. Cl. D83—1 V

FIG. 4

FIG. 5

FIG. 6

FIG. 1

FIG. 2

FIG. 3

FIG. 7

FIG. 1 is an elevation view of a specimen collector or similar article having a specimen receptacle and a collapsible bracket for supporting the specimen receptacle on a toilet bowl or the like, showing my new design;

FIG. 2 is an elevation view of the device shown in FIG. 1 with the bracket in its collapsed position for storage;

FIG. 3 is a plan view of the collapsible bracket shown in FIG. 1 with the specimen receptacle removed;

FIG. 4 is an elevation view of the bracket shown in FIG. 3;

FIG. 5 is a bottom view of the bracket shown in FIG. 3;

FIG. 6 is an end view of the bracket shown in FIG. 3; and

FIG. 7 is a top perspective view of the specimen collector and collapsible bracket in assembled relationship.

I claim:

The ornamental design for a specimen collector or similar article, substantially as shown.
